UNITED STATES PATENT OFFICE.

WILLIAM M. SCHOLL, OF CHICAGO, ILLINOIS.

PAD FOR FOOT TREATMENT.

1,288,225.

Specification of Letters Patent. Patented Dec. 17, 1918.

Application filed August 28, 1916. Serial No. 117,211.

To all whom it may concern:

Be it known that I, WILLIAM M. SCHOLL, a citizen of the United States, residing at Chicago, in the county of Cook and State of Illinois, have invented certain new and useful Improvements in Pads for Foot Treatment, of which the following is a specification.

My invention relates to improvements in corn and bunion shields.

10 One of its objects is to provide a pad, for relieving pressure of the shoe upon the affected area, that will not decrease the flexibility of the wearer's foot.

Another object is to provide a pad of 15 cheap construction, readily made in various sizes and shapes differing in detail, for efficient fitting of individual cases, and one that will effectively retain its position with respect to the foot under all conditions of use.

20 Other and further objects of my invention will become apparent from the following description, taken in conjunction with the accompanying drawings, wherein—

Figure 1 is a bottom plan view of a pad;

25 Fig. 2 is a top plan view thereof;

Fig. 3 is a section on line 3—3 of Fig. 2; and

Fig. 4 is an end elevation of the pad.

The pad, generally indicated at 10, I make 30 preferably of a single piece of flexible, fibrous, elastic material, such as rather stiff felt, shaped suitably by die-bending and skiving the crown and recess surfaces. The pad is formed to taper from one end to an 35 abrupt shoulder at the other end and in the high end is formed a cavity or recess to receive the bunion crest or corn, said cavity opening to both the end and the bottom of the pad. Thus, from a marginal portion 11, 40 about semi-ellipsoidal in plan, and terminating at one end at the abrupt shoulder 12, the crown or upper surface of the pad curves up smoothly, both toward the longitudinal axis and toward the shoulder 12; the curves

45 being greater or less of course according to variations in the desired thickness of the pad in proportion to its length. The under-
surface of the pad is preferably flat, as at 14 at its curved end, and at the shoulder end a 50 recess or cavity 15, preferably semi-circular or semi-ovate in plan, and with a concavely curved upper surface, 16, is cut into the pad, opening to the bottom and to the pad-end.

For many purposes it is desirable to cut 55 away, semicircularly, as at 17, the thin wall

between the crown surface and the crest of the recess 15, so that at its thicker end the pad provides two horns 18, arched in transverse elevation as shown in Fig. 4.

In use the pad is preferably worn under 60 the stocking. Its flat surface 14 may be adhesive-coated if desired, but usually this is not necessary. The skinless, fibrous crown surface of the felt affords a good frictional resistance to displacement, and the confor- 65 mation of the pad tends to prevent its shifting under walking conditions. The pad is applied, say to a bunion at the great toe joint, with the body of the pad lying along the side of the foot in rear of the bunion 70 and its horns 18, 18' straddling the node of the bunion. The shoe pressure is adequately removed from the affected painful area, yet the joint may flex unobstructedly, and the pad, since it does not materially change 75 shape or alignment of its parts under such joint-flexure, is not subject to be shifted from its intended position.

It will be apparent that changes in detail may be made in the embodiment of my invention without departure from its spirit and within the scope of the appended claims.

What I claim is:

1. A bunion or corn shield comprising a body thick at one end and tapering toward 85 the other end, said body having a recess in its thick end, thereby, reducing the thickness of the body gradually and uniformly toward the thin end.

2. A bunion or corn shield comprising a 90 body thick at one end and tapering toward the other end, said body having a recess in its thick end to reduce the thickness, and said recess opening both to the bottom and the end of said body.

3. A bunion or corn shield comprising a body thick at one end and tapering toward the other, said thicker end having longitudinally projecting horns, and there being a recess open to the end and another recess 100 open to the bottom of the body, in said thicker end of the body.

4. A pad of homogeneous fibrous material providing a semi-ellipsoidal body having a crown surface rising curvingly from the 105 margins at the sides and one end to a crest at the abrupt thicker end, said thicker end having a recess formed therein to reduce the thickness and leaving the curved surface intact.

5. A pad of homogeneous fibrous material providing a semi-ellipsoidal body having a crown surface rising curvingly from the margins at the sides and one end to a crest 5 at the abrupt thicker end, said thicker end having a recess formed therein of greatest depth at the abrupt thicker end and curvingly decreasing in depth to a point intermediate the ends, said pad having an opening formed therein through the crest of the

pad to the recess, dividing the abrupt end of the pad into horns.

In testimony whereof I hereinunto set my hand in the presence of two subscribing witnesses.

WILLIAM M. SCHOLL.

In the presence of—

STANLEY W. COOK,
MARY F. ALLEN.
